HEAD RAIL CONSTRUCTION

Keator McCubbin, Elkhart, Ind., assignor to Henry Weiss Manufacturing Company, Inc., Elkhart, Ind., a corporation of Delaware

Filed June 23, 1961, Ser. No. 119,206

1 Claim. (Cl. 189—36)

This invention relates to structures comprising stiles and associated members used in the construction of cubicles or small enclosures, such as toilet and dressing compartments, shower stalls, and the like, and is concerned more particularly with the stiles and the associated head rail therefor.

It is known to provide small compartments of the above character by means of partitions extending from an adjacent wall to floor anchored stiles tied together at their upper ends by a reinforcing head rail, and arranged in a row, suitably spaced apart. According to the present practice, the stiles are formed of sheet steel of approximately twenty gauge thickness and are of approximately elongated rectangular or oblong cross section with front and back panels connected by rounded side panels or molding strips of substantially less width than the front and back panels, usually about one-half the width thereof. The front and back panels extend upward beyond the side panels and receive between them an upwardly opening reinforcing channel member of about sixteen gauge steel seating on the upper edges of the side panels. The upper ends of the stiles are tied together by a reinforcing head rail of rectangular cross section with a flat top wall, formed of lockseam steel tubing of about twenty gauge thickness. The head rail seats in the reinforcing channel members, the latter and the head rail being secured to the extensions of the inner or rear panels of the stiles by sheet metal screws. Difficulty has been experienced with the usual structure above described. It has been found that boys frequently use the head rail, which may readily be gripped by the hands without serious discomfort, as a horizontal bar for performing gymnastics. The head rail is thus subjected to twisting and rocking movements under load. That results in bending outward of the outer arms of the channel members and of the upward extensions of the outer or front panels of the stiles. The head rail then rests loosely in the upper ends of the stiles and its reinforcing function is largely lost, and the distorted upper ends of the stiles present an unsightly appearance. That necessitates repair, which is costly as well as interfering with use of the compartments, replacement of the head rail often being necessary due to distortion thereof.

My invention is directed to a head rail construction which avoids the objections to the presently used construction, above described. To that end I provide a head rail which can not be used as a horizontal bar without serious discomfort to a person attempting to use it for that purpose, and which cooperates with the upward extensions of the stiles to resist bending of such extensions if the head rail is used as a horizontal bar. The head rail of my invention also has the advantage that the top wall thereof presents downwardly sloping surfaces which will not accumulate dust and may readily be cleaned, in contrast to the flat top wall of head rails presently used, which readily accumulate dust and are difficult to clean. Further objects and advantages of my invention will appear from the detail description.

In the drawings:

FIGURE 1 is a front view of a row of floor-anchored stiles tied together by a head rail construction embodying my invention;

FIGURE 2 is a sectional view, on an enlarged scale, taken substantially on line 2—2 of FIGURE 1; and

2

FIGURE 3 is a sectional view, on an enlarged scale, taken substantially on line 3—3 of FIGURE 1.

I have illustrated the head rail construction of my invention, by way of example, as embodied in a structure comprising a row of appropriately spaced stiles 5. The stiles 5 are formed of twenty gauge steel and are of generally rectangular or oblong cross section, having flat front and back panels 6 and 7 joined together by arcuate side panels or molding strips 8 one of which is attached to back panel 7 by a lock seam 9; as shown in FIGURE 2. The lower ends of stiles 5 are anchored to a floor 10 in any suitable known manner, preferably, but not necessarily, by the anchoring means disclosed in the co-pending application of John E. Vawter, for Stile and Mounting Therefor, Serial No. 74,106, filed December 6, 1960, now Patent No. 3,108,664, patented October 29, 1963. The stile 5 preferably is provided with a sound deadening core or filler 5a, formed of corrugated paper board or any suitable material, fitting between panels 6 and 7 and cemented thereto, as is known.

The panels 6 and 7 are provided with extensions 6a and 7a, respectively, projecting above the side panels 8. A head rail 12 fits snugly between the extensions 6a and 7a and seats upon the tops of the side panels or strips 8, as shown in FIGURE 3. The head rail 12 is preferably an aluminum alloy extrusion and is of generally rectangular or oblong cross section. It comprises side walls 13 joined at their upper edges by a top wall 14 and joined at their lower edges by a flat bottom wall 15 which seats upon the upper edges of side panels 8. The top wall 14 is of approximately inverted flattened V-shape in cross section providing two downwardly and outwardly inclined arms 16 of arcuate cross section and curved inwardly of head rail 12. The upper portions of arms 16 are integrally joined together by a ridge 17 providing an upwardly directed peak presenting a rather sharp edge extending lengthwise of top wall 14 centrally thereof. The lower portion of each arm 16 of top wall 14 extends a short distance outward beyond the corresponding side wall 13 and is provided with a downwardly extending narrow flange 18 disposed in spaced parallel relation to such side wall 13. The flanges 18, in cooperation with the contiguous portions of the rail 12, provide downwardly opening channel members at the top of the respective side walls and of a width to engage tightly over the upper edge portions of the upward extensions 6a and 7a of the panels 6 and 7, respectively, with the bottom wall 15 of rail 12 seating upon the upper ends of side panels 8 and the upper ends of extensions 6a and 7a abutting the base elements of the channel members.

The row of stiles 5 is disposed in spaced parallel relation to a building wall or analogous structure, with partitions extending between such wall and the stiles to provide the desired compartments; as is known. Doors may or may not be mounted upon the stiles, as desired or as may be required. It may be assumed that in the illustrated embodiment of my invention, the compartments are shower stalls or other compartments not provided with doors. Neither the building wall or analogous structure, nor the partitions, above referred to, are shown, both being well known and neither constituting an essential feature of my invention, which resides in the head rail and stile construction.

The head rail 12 fits snugly between the extensions 6a and 7a of the front and back panels 6 and 7, respectively, of the stiles 5, with its bottom wall seating upon the upper ends of side panels 8 and the upper edge portions of extensions 6a and 7a fitting tightly in the channel members at the upper edges of walls 13. The extension 7a of the back or inner panel 7 of each of the stiles 5 is secured to the inner or back wall 13 of head rail 12 in a suitable manner, conveniently by a sheet metal screw 19.

The downwardly and outwardly curved arms 16 of top wall 14 render it difficult to obtain an effective finger grip on head rail 12, and the sharp edge or ridge 17 would tend to cut into a hand grasping head rail 12 for the full width thereof; both features discouraging use of the rail as a horizontal bar. If it be assumed that head rail 12 be so used to limited extent by being gripped for its full width, the downwardly and inwardly arched arms 16 of top wall 14 would carry the load under compression to substantial extent thereby reducing likelihood of objectionable distortion of rail 12. Further, any tendency to twisting or side-wise tipping of head rail 12 would place the extensions 6a and 7a of the panels 6 and 7, respectively, of the stiles 5 under compression, due to the seating thereof against walls 13 of rail 12 and in the channels at the upper edges of those walls, and the seating of rail 12 on the upper ends of side panels 8 of the stiles 5. Accordingly, outward bending of extensions 6a and 7a, with resultant looseness of the head rail 12 is effectively precluded under all conditions normally encountered. The head rail 12 and the extensions 6a and 7a are mutually reinforcing thereby providing a structure of adequate strength without the usual reinforcing channels presently used, which may be omitted with a corresponding saving in metal. The downward and outward slope of arms 16 of top wall 14 of head rail 12 possesses the further advantage that such wall can readily be cleaned and materially reduces likelihood of accumulation of dust thereon compared to a flat top wall.

It will be understood that changes in detail may be 30

resorted to without departing from the field and scope of my invention and I intend to include all such variations, as fall within the scope of the appended claims, in this application in which the preferred form only of my invention has been disclosed.

5 I claim:

In a stile-to-rail joint, a stile of substantially oblong cross section comprising front and back panels joined by side panels, said front and back panels having extensions 10 projecting upward above said side panels, and a head rail of substantially rectangular cross section comprising flat side walls and top and bottom walls joining said side walls, said head rail having downwardly extending flanges joined to and spaced from said side walls thereof defining therewith downwardly opening channel members, said head rail fitting snugly between said upward extensions of 15 said front and back panels with its side walls in contact with the inner faces of said extensions and its bottom wall seating on the upper ends of said side panels, said extensions of said front and back panels fitting tightly into said channel members and in cooperation therewith and with the side walls of said rail restraining said extensions against transverse bending under load applied to said rail.
